UNITED STATES PATENT OFFICE.

CHARLES T. BRANHAM, OF VALLEY CENTER TOWNSHIP, PAWNEE COUNTY, KANSAS.

FENCEMAKER'S TOOL.

Application filed December 12, 1921. Serial No. 521,822.

To all whom it may concern:

Be it known that I, CHARLES T. BRANHAM, a citizen of the United States, residing at Valley Center Township, in the county of Pawnee and State of Kansas, have invented certain new and useful Improvements in Fencemakers' Tools, of which the following is a specification.

This invention relates to combination tools especially designed for fencemakers' uses.

The object of the invention is to provide a simple and efficient tool of this character which may be used for splicing a broken fence wire, as a staple puller, a wire twister and cutter, and also as a hammer.

Another object is to provide a tool of this character, which when the parts are assembled cooperate with each other to form a tool of compact and symmetrical appearance.

With these and other objects in view, the invention consists in certain novel features of construction as hereinafter shown, described, and claimed.

In the accompanying drawings:

Figure 1 represents a perspective view of the tool constituting this invention shown applied in the position assumed in the first step of splicing a broken wire;

Fig. 2 is a perspective view taken from the rear showing the tool in the position assumed after the wire has been spliced and before the tool is removed;

Fig. 3 is a perspective view taken from the front end showing the tool in the act of being used as a staple puller;

Fig. 4 is a side elevation of the tool head with the jaws shown in open position for use as a wire cutter with parts broken out and in section; and

Fig. 5 shows a front elevation of a spliced barbed wire which was accomplished by the use of this improved tool.

The tool constituting this invention comprises two jaw members 1 and 2, each of which is provided near its head end with a discoid portion 3. These discoid portions 3 bear laterally against each other and are pivotally connected by means of a pin 4. Each of the members 3 is provided at its periphery adjacent the member carried thereby with a wire cutting notch 5 which notches are adapted to cooperate in severing strands of wire in a well known manner. These notches are so positioned that when

the members 1 and 2 are opened as shown in Fig. 4, the notch in one member 3 will register with that in the other to form a continuous groove to receive the wire. 60

The member 1 is provided with a handle portion 6 and member 2 with a similar portion 7 which handles extend from the members 3 at points diametrically opposite the members 1 and 2 carried by said discoid 65 portions.

The member 1 has its discoid head portion 3 arranged with the outer face thereof flush with said portion, while the inner face of said portion is about one-half the 70 thickness of said member 1 and the adjacent inner portion of the member 1 is curved to conform to the periphery of the discoid portion 3 carried by the member 2 which is similarly shaped to member 1 and 75 receives the discoid portion 3 of said member 1, so that the parts when pivotally connected as shown in the drawing, will provide a hammer head and handle of uniform thickness throughout as is shown clearly 80 in Figs. 1, 2 and 3.

The member 2 is provided at its front end with a conoidal-shaped portion 2', the apex 8 of which is eccentrically disposed with respect to the axis of the member 2, and is 85 further extended obliquely to this axis, as shown, and is designed to be used as a staple puller. The member 1 is provided at its head end with an annular flange to provide a hammer head 9 which may be used for 90 driving nails, staples, and for various other purposes. The hammer head 9 has a bore 10 extending transversely therethrough and is designed to receive a wire W to be used in tightening and drawing together two 95 ends of a broken fence wire or for twisting any wire to be twisted.

When this tool is to be used in connecting two ends of a broken fence wire to be spliced, the broken wires w have loops L 100 formed at the ends to be connected and the wire W is engaged with said loops and secured thereto by twisting the ends as shown in Figs. 1 and 2. It is of course understood that the wire W is first passed 105 through the bore 10 in the member 1 before the ends thereof are secured in the manner above set forth. The tool being then in the position shown in Fig. 1, it is rotated by turning the handle thereof, winding up 110 wire W on the hammer head, the portion 11 of which forms a drum for said wire as is

shown clearly in Fig. 2. As the wire W is wound on the drum, the ends of the broken wire will be drawn toward each other and when stretched sufficiently taut 5 may be secured by splicing wire shown at 12, which is passed several times through the loops L and secured by twisting the ends around the wires as shown in Fig. 5. After the broken wire ends have been so 10 spliced, the drum may be unwound from the wire W and said wire detached from the loops.

When this tool is to be used as a staple puller, the tine 8 is inserted through the 15 staple S and the tool manipulated in the usual manner for extracting staples.

The manner of using the tool as a wire cutter is obvious by an inspection of Fig. 4 as has been fully described above.

The preferred embodiment of the invention is disclosed in the drawings and set forth in the specification, but it will be understood that any modifications within the scope of the claimed invention may be made in the construction without departing from 25 the principle of the invention or sacrificing any of its advantages.

What is claimed is:

In a fence maker's tool, a head formed at one end with a conoidal-shaped staple remover, the apex of which is eccentrically disposed and extended at an oblique angle with respect to the axis of said head to form 30 a staple-engaging member.

In testimony whereof, I affix my signature hereto.

CHARLES T. BRANHAM.
